NILS O. LINDSTROM, OF JERSEY CITY, NEW JERSEY, ASSIGNOR TO ALONZO B. SEE AND WALTER L. TYLER, OF NEW YORK, N. Y.

ELECTRIC-ELEVATOR CONTROL.

SPECIFICATION forming part of Letters Patent No. 784,869, dated March 14, 1905.

Application filed November 17, 1904. Serial No. 233,089.

To all whom it may concern:

Be it known that I, NILS O. LINDSTROM, a citizen of the United States, residing at Jersey City, in the county of Hudson and State of New Jersey, have invented certain new and useful Improvements in Electric - Elevator Control, of which the following is a full, clear, and exact description.

This invention relates to push-button-control systems for electrically-operated elevators; and the primary object of the invention is to provide a control system by which persons desiring to use the elevator may operate it themselves without the aid of a special elevator-man and may travel from floor to floor without liability of accident and without interference between passengers already occupying the car and others that may endeavor to obtain the use of the car at the same time. For a perfectly safe system it is necessary that after one would-be passenger has pushed a button to bring the car to him another cannot interfere with the movements of the car in any manner until the first passenger has obtained the car, moved thereon to his destined floor, passed out of the car, and finally closed the shaft-door behind him. If it is at all possible at any moment between the first push of the button and the final closing of the door at the destined landing for another passenger to interfere with the car, the system is unsafe.

The invention herein described provides a perfectly safe system of push-button control. In the accompanying drawing I have represented conventionally the apparatus and various circuits used in carrying out my invention.

The electric motor for moving the elevator is indicated at M, of which R is a sectional resistance in the armature-circuit for graduating the start of the motor in the usual way.

S is a solenoid having a core s attached to the rheostat-arm r, so that when the solenoid is energized the resistance will be cut out of the armature-circuit and the motor permitted to gradually attain its highest speed. It will be understood that a dash-pot or any other

contrivance may be used in connection with this solenoid to retard the movement of its core. The rheostat-arm is pivoted and carries an extension r', to which is affixed a blade adapted to engage two contacts 1 and 2 when the elevator is in its normal or unused condition.

55

t is a switch-lever arranged above the rheostat-arm and pivoted in a position where it will be engaged by a roller or lug r² on the core s when the latter is raised by the energizing of the solenoid S. The switch-lever t bears at one end against a contact 3, the opposite end of the lever being heavier in order to normally hold it in this position. When engaged by the roller r², however, lever t is moved so that it will leave contact 3 and connect with contact 4.

The regular "up" and "down" solenoids, whose function it is to close the main switch and direct current through the motor in a manner to send the car either up or down, as required, are indicated by the words "Up" and "Down." This apparatus and its mode of operation is well known in the art and forms no part of the present invention. The car is indicated by the dotted rectangle and contains one push-button for each floor of the building; as well as any other buttons, such as a stop-button for emergency, that may be desired. None of these latter, however, is shown. On each floor of the building or at each elevator-landing is placed a push-button, and these correspond, respectively, with the buttons in the car, they being connected in parallel circuit with each other and the circuit-wires passing through a flexible cable in the usual manner. The push-buttons at the landings are indicated by "1st floor," "2nd floor," "3rd floor," &c. At each landing the door permitting access to the shaft operates a cut-out switch, indicated in the drawing by

"Door-switch." These door-switches are all in series, so that one of them is all that need be shown in the drawing. The gate on the car itself, which is usually closed while the car is in motion, may also operate a cut-out switch, indicated in the drawing by "Gate-switch;"

but as both the gate and the door are not always used we will consider only the switch connected with the landing-door. The door-switch and the gate-switch are shown in the 5 drawing as in series with each other, and it will be seen from the circuits hereinafter traced that they are also in series with the floor push-buttons and the corresponding car push-buttons, while, as before explained, the car 10 and floor buttons are in parallel with each other. There are also provided, corresponding to each floor, magnetic switches m , m' , m'' , &c., consisting of an electromagnet or solenoid whose armature carries a cross-head o , 15 adapted to bridge two contacts p and p' , the function of these switches being to hold a given circuit closed after it has first been closed by hand at one of the push-buttons. In connection with this system I use another piece of 20 apparatus well known in the art as a "regulator." This is a frame or body mounted usually near the motor and driven by it at a speed corresponding to or in proportion with that of the car. This regulator contains a series 25 of switches, one for each floor of the building, and its function is to open the control-circuit whenever the car reaches a floor corresponding to a push-button that may have been operated by the passenger. Its function is also to 30 set the switches at each floor as the car passes, so that the current will be sent through either the up or down solenoid, depending upon whether the car is above or below the floor to which it may be called. The switches on the 35 regulator are mechanically operated by cams, each switch for the intermediate landing consisting of a lever and a pair of contacts on each side of it. When the car arrives at a landing, the switch-lever is thrown to the mid- 40 position between both pairs of contacts and opens any circuit that may have been previously established through either pair of contacts. When the car moves upward from the landing, it throws the switch-lever to one side, 45 closing the contacts that control the circuit to the down solenoid, and after the car moves downward from a given floor the other pair of contacts is closed to complete the circuit when necessary through the up solenoid. With 50 this brief description of the regulator the operation of the system will be described and the circuits at the same time pointed out.

With the parts in the position shown in the drawing the elevator-car is supposed to be 55 standing at the top-floor landing, the switch in the regulator corresponding to the top floor being open and the switches corresponding to all other floors of the building (only one intermediate floor being shown) having been set 60 in position to energize the down solenoid by the car in traveling upward to the top floor. Suppose a person on the first floor desires to be carried to the third floor. He will push the button "1st floor" on the landing. This

will close the following circuit: from the 65 positive main by wire 5 through the door-switch at the third-floor landing, wire 6, contacts 1 and 2, wire 7, wire 8, first-floor landing push-button, wire 9, wire 10, switch-magnet m , wire 11, regulator-switch 1, wires 12 70 and 13, down solenoid, wire 14, clips 18 of the up solenoid to the negative main. This will energize switch-magnet m and the down solenoid. Magnet m will at once close a branch from the wire 5 by way of resistance 75 q and wire 17 to the wire 10, so that when the passenger releases the push-button at the landing the circuit before traced through the switch-magnet m and the down solenoid will be maintained. The down solenoid being energized, its core is lifted, the circuit through the up solenoid is broken at the clips 16, and main circuit through the motor is closed through wires 19 20 21, resistance R , resistance-arm r , and wire 22. At the same time 80 also a circuit is closed by the armature of the down solenoid through the solenoid S by way of wire 23, contact 3, switch-lever t , and wire 24. The motor will now start and lower the 85 car, the core of solenoid S being lifted until 90 all of the resistance is out of the armature-circuit and the motor is operating at full speed. At the moment the core s lifts the manual control-circuit is broken at the contacts 1 and 2 by the removal of the blade from 95 contact with those clips, and at the upper end 100 of the stroke of the solenoid-core the roller r' strikes switch-lever t and throws it out of connection with contact 3 and into connection with contact 4. The wire 23 therefore becomes dead, but the current continues to flow 105 through solenoid S by way of resistance q and contact 4. While the car is in motion it will 110 be seen that another operation of any of the floor push-buttons will not in any manner interfere with the movement of the elevator, 115 since the control-circuit 6 7 is open at the points 12. When the car reaches the first floor, the regulator opens the circuit at the switch 1, thus de-energizing switch-magnet m and the 120 down solenoid. The latter drops its armature and opens the motor-circuit, allowing the car to come to rest; but the core of solenoid S still remains up, because it is not now dependent upon the main switch actuated by the down solenoid. Hence the contacts 1 and 2 still remain open, 125 and the operation of any of the push-buttons at other floors will not yet affect the car. The person at the first floor desiring to use the car will now open the landing-door and step into the car. The movement of the door opens the circuit of solenoid S at the door-switch, which permits the solenoid-core to fall and close the manual control-circuit at 1 2, and at the same time throw the resistance all into 130 the armature-circuit. On entering the car the passenger closes the landing-door, and thereby completes the control-circuit at all 135

points except at the push-buttons. He now pushes the third-floor button in the car and completes the following circuit: from the positive main by wires 5, 6, and 7, third-floor 5 push-button in the car, wire 24, switch-magnet m^2 , wire 25, regulator-switch 3, (which was closed automatically when the car left the third floor,) wires 26 and 27, up solenoid, wire 28, clips 16, wire 29, and wire 15 to the negative main. The motor then starts as before, the connections being such as to reverse its 10 direction of rotation, so that the car will move upward, (these connections not being shown for the up solenoid in the drawing.) The 15 car will proceed uninterruptedly as before until it reaches the third floor, where upon the switch in the regulator being automatically opened the up-solenoid circuit is de-energized and the motor comes to a stop, leav- 20 ing the core of solenoid S hanging up as before. No other would-be passenger can in the meantime stop or start the car by operating the buttons and the passenger is protected until he steps out onto the landing at the third 25 floor, for in opening the door he disables the control-circuit at the door-switch, notwithstanding the fact that he at the same time permits the core of solenoid S to fall and close the control-circuit at contacts 12. Upon clos- 30 ing the door of the landing the car is then at the service of a person on any other landing, for the door then closes the door-switch and finally completes the control-circuit except at the push-buttons.

35 The novelty claimed for my invention resides in the construction and operation of the resistance-solenoid S, whereby its core is retained in its uppermost position after the motor is stopped, and the control-circuit is con- 40 tinued disabled at the contacts 1 and 2 until the passenger has opened and closed the land- ing-door. I am aware that the same result has been accomplished in other ways; but, so far as known to me, never with so simple ap- 45 paratus as I have provided—that is to say, I use the resistance-solenoid for the double purpose of disabling the control-circuit and of controlling the starting resistance. This, in connection with the switch t for maintaining 50 the current through the solenoid after it has been cut off from the motor, constitutes my invention.

The resistance g is used to prevent heating of the solenoid S in case for any reason the 55 elevator-door is not opened promptly.

It will be understood that the main switches operate the brake and any other of the usual circuits; but as these have nothing to do with the invention they are not shown.

Having described my invention, I claim— 60

1. In an electric elevator, a manually-operated control-circuit including a door-circuit breaker, a resistance-solenoid adapted to be thrown into circuit with said door-circuit breaker, and itself adapted to control said 65 manually-operated control-circuit.

2. In an electric elevator, the combination of a solenoid adapted to control the armature resistance and the elevator-control circuit, and two circuits both including said solenoid, one 70 of which is closed and opened simultaneously with the closing and opening of the motor-circuit and the other of which includes a door-circuit breaker.

3. In an electric elevator, the combination 75 of a solenoid adapted to control the armature resistance on the elevator-control circuit, and two circuits both including said solenoid, one of which is closed and opened simultaneously with the closing and opening of the motor- 80 circuit and the other of which includes a door-circuit breaker, and a switch adapted to throw the solenoid from one circuit to the other, substantially as described.

4. In an electric elevator, the combination 85 of the car-motor, a rheostat therefor, a solenoid adapted to operate the rheostat, a control-circuit common to all landings and adapted to be opened by said solenoid when it is energized to start the motor, and means for 90 maintaining the solenoid energized after the motor is stopped.

5. In a push-button-control system for elevators, the combination of an electromagnet adapted to control the motor resistance, two 95 circuits each including the resistance-magnet, one of said circuits being controlled by a motor-controlling switch and the other including a cut-out actuated simultaneously with the elevator-car door. 100

6. In an electric elevator, a motor, an armature-resistance solenoid, a main switch adapted to close the circuit through the motor and the solenoid simultaneously, an auxiliary switch actuated by the resistance-solenoid and 105 adapted to direct current through the solenoid independently of the main switch, a manually-operated control-circuit and means whereby the resistance-solenoid will hold the control-circuit open while it is holding the auxiliary switch in a position to direct current through the solenoid. 110

In witness whereof I subscribe my signature in the presence of two witnesses.
